UNITED STATES PATENT OFFICE.

HEINRICH DREWELL, OF CHARLOTTENBURG, GERMANY, ASSIGNOR TO SCHNELLSETZ-MASCHINENGESELLSCHAFT MIT BESCHRÄNKTER HAFTUNG, OF BERLIN, GERMANY.

TYPE-SETTING MACHINE.

970,694.

Specification of Letters Patent. Patented Sept. 20, 1910.

Application filed December 9, 1908. Serial No. 466,707.

To all whom it may concern:

Be it known that I, HEINRICH DREWELL, a subject of the German Emperor, residing at Charlottenburg, near Berlin, Germany, have invented new and useful Improvements in 5 Type-Setting Machines, of which the following is a specification.

The subject-matter of the present invention is improved means for canceling or 10 eliminating the action of incorrect groups of holes in register bands for setting type automatically.

Means are known for making register bands for automatically operating type-setting machines, in which the register band is 15 perforated by depressing keys and in which the text which is set is simultaneously written on a type-writer in order to make it possible for the composer to check his work. 20 Further, the arrangement of a special device, such as a key or the like, is known for punching a symbol in the band after an incorrectly written and perforated line, by means of which symbol the group of holes 25 representing the incorrect line is made inoperative. In this manner the composer is able to eliminate errors in his work.

The present invention consists in a further improvement of these means, and an 30 important object is to so simplify the work of the composer that a typist is able to make or prepare composition ready for printing.

In the means known heretofore there are 35 certain difficulties which are connected particularly with the justification of the lines. In order to obtain a good appearance of the matter, when setting type all the lines must be composed as full as possible. Consequently the composer is frequently in doubt 40 whether a syllable which is to be set can or cannot be got into the begun or nearly filled line. If he attempts to set up the syllable in the line and recognizes, after he has begun, that it is too long, in the case of the means known heretofore he had to remove a whole 45 line and set it again. Apart from the unnecessary loss of time which is caused, the danger that errors may occur in the composition is still more increased, since when the 50 same text is written repeatedly, when the composer involuntary writes more rapidly than generally, errors very easily occur as experience shows. Also the removal of entire lines on account of one single error occasions unnecessary loss of time. An error 55

occasioned by depressing the wrong key is, as a rule, quickly recognized by the composer or typist, so that he can at once remove the error in so far as a suitable device is present for this.

In order to remedy the above mentioned defects, according to the present invention besides the device for canceling entire lines, a second device is arranged for canceling or eliminating the word last set up. For special cases another device is also provided which admits of individual characters or individual symbols on the register band being made inoperative. This device is of special importance because there are provided on 70 the apparatus for perforating the band, in addition to the character keys, a series of keys, levers or the like for other purposes, for example for the end of a line, changing to another sort of type, justifying the lines, 75 and so on. These keys also may be used incorrectly. Since the depression of such a key causes a symbol to be perforated in the register band, the effect of these keys being used incorrectly would also be transferred 80 to the type-setting machine. Therefore according to the present invention the concerned perforated symbols are able to be made inoperative individually.

When removing or eliminating lines, 85 words and individual characters by rendering inoperative the appertaining places of the register band special regard must be paid to justifying the lines, the device for indicating the space for the type having to 90 be correctly set in each case. With regard to the line this is very simple, since after each admissible or inadmissible line the type-space indicator is brought into the position which it has to take up at the commencement of a line, which can take place automatically. When removing or eliminating individual words another device is required. Since the words are of different length, the composer must be able to know how long 95 the last written word is and how much the type-space indicator has to be moved backward when this word is removed. The same holds good when removing individual characters. For this instance the invention provides special means. These means substantially necessitate the employment of a type-writer with "systematic" movement of the paper carriage as type-space indicator, the word "systematic" here and hereinafter de- 100 105 110

noting: according to types of different width. When each key is depressed the paper carriage is shifted a certain distance, corresponding to the breadth of the letter 5 which is written with the key and set up, but so however that the distance which the paper carriage is shifted is in a fixed proportion to the breadth of the printing letter which is to be set up. The same relation 10 then of course also exists between the word-lengths of the written line and of the line which is to be composed later by means of the band. Now when removing or eliminating a word or a letter the paper carriage 15 must be set backward the length of the written word or individual character. It is preferable, when removing a word, to set the paper carriage backward and to perforate the symbol in the register band by 20 which the word is removed, with the same lever or the same key. When one single character is being removed such a combination of the two actions can be dispensed with, because the carriage can be placed 25 backward a small amount more simply with the aid of another device, and because the means for removing one single perforated symbol is used less for removing characters than for removing the above mentioned auxiliary symbols in the register band. In the 30 latter case, however, it is not necessary to rectify the position of the paper carriage or type-space indicator.

For putting the invention into practice 35 band perforating machines and typewriters of optional construction may be employed in so far as the latter are provided with means for shifting the paper carriage systematically, namely according to types of different 40 width.

In order that the invention may be clearly understood reference will be made to the accompanying drawings in which one embodiment is represented by way of example 45 and in which a typewriter of known kind is shown in combination with a known device for perforating bands. When the key-levers of the typewriter are depressed electric contacts are closed and corresponding 50 electromagnets of the perforating device are operated.

In the drawings: Figure 1 is a vertical side elevation of the combined machine, part of the frame of the machine being shown 55 broken away; Fig. 2 is a front elevation of means used for canceling entire words; Fig. 3 is a front elevation of means used for canceling entire lines, whereas Fig. 4 is a diagram of connections which will be explained 60 hereafter, and Fig. 5 is a detail shown in front elevation.

Referring to the drawings, the combined typewriter and perforating machine has a common body or frame 1 which carries in 65 front the typewriting mechanism. This

consists of key-levers 2 which are connected by rods 3 with the type-levers 4. When the key 5 is depressed the types 6 attached to the levers 4 strike against the ribbon 7 and press it against the paper placed around the platen roll 8. The axle 9 of the roll 8 is journaled in the side parts 11 of a frame 10. The frame 10 is revoluble around the axle 15 and is journaled in the frame 16 of the paper carriage. The latter runs with the 75 wheels 17 and 18 on rails 19 and 20, the latter being attached to the body of the typewriter. The paper carriage is moved in known manner by a spring. For checking the movement of the carriage four ratchet 80 wheels 21, 22, 23 and 24 are arranged. Each of these is connected with a bevel wheel 25. Each two bevel wheels 25 act on a planet wheel 26, the pivots of which are attached on a bush or sleeve 27 revoluble 85 freely around the axle 30. The two sleeves 27 each carry a bevel wheel 28. These two bevel wheels mesh with a planet wheel 29, the pivot of which is attached to the axle 30. The latter carries two ratchet wheels 31, 32, 90 and a worm wheel 33 revoluble freely on the axle 30, the latter wheel being so connected with the wheel 32 by a click or pawl 34 that it must follow the rotation of the wheel 32 in one direction, but can rotate freely in the 95 opposite direction however. The latter event occurs when the paper carriage is pulled backward, the axle 30 being prevented from rotating by a pawl 31 which engages in the wheel 31. The wheel 33 is a 100 worm wheel and engages in a screw spindle 35. The latter is revoluble in the frame 16 of the paper carriage, but is journaled immovable in the longitudinal direction and has at its ends a knob 36 with which it can 105 be rotated by hand. The spindle 35 acts in known manner during the operations of typewriting and as a rack when it is shifted by the wheel 33, but can be used for exactly adjusting the paper carriage to one definite 110 point by its being rotated by means of the knob 36. In this event the spindle 35 acts as a screw and the stationary toothed wheel 33 in known manner as a nut. On the ratchet wheels 21, 22, 23, 24 there act double 115 pawls 40, 41, 42, 43 which are revoluble around axles 44. With each of these pawls there is connected a lever-arm 45 with which draw rods 46 engage. The latter, again, lead to four universal bars 47 which are 120 journaled below the key-levers. When a key 5 is depressed, the a pertaining key-lever 2 acts on one or more of the universal bars 47 and shifts the paper carriage different distances in known manner. With 125 the typewriter there is connected, further, a punching device. The movement of the keys is transmitted to the punching device with the aid of an electric current. For this purpose there is attached to each key-lever a 130

hook 50 which engages under the extension 51 of a lever 52 made of electrically insulating material. The lever 52 is attached on a spring 53 and is connected through this with a terminal 54. Below the lever 52 and the left-hand end of the spring 53 there is arranged a contact screw 55 which is movable in a terminal 56. The terminals 54 and 56 are attached on the ebonite plate 57. When 10 a key is depressed the hook 50 releases the lever 52 and the spring 53 contacts with the screw 55. All the terminals 54 and 56 are connected in suitable manner with the electromagnets 58 of the punching device.

15 Opposite each of the electromagnets 58 there is an armature 59 which is mounted on a bell-crank lever 60. The horizontal arms of the bell-crank levers 60 carry draw bars 61, to the upper ends of each of which a hook 62 is pivotally connected. The hooks 62 have horizontal arms with which springs 64 are connected. The upper ends of the hooks 62 engage catches or pawls 65. The latter serve for keeping four-armed levers 66 in 20 their normal position against the action of springs 67. If one of the electromagnets 58 is energized, it attracts its armature and, by means of the rod 61, causes the corresponding hook 62 to withdraw the catch 65 opposite to it from one of the levers 66. Consequently this lever rotates around the axle 68 and causes its arm 69 to drive the punch 70 into the paper. At the same time the bar 71 is thrown back by the lever 66, so that with 25 the aid of a known coupling device, the axle 72 comes into operation and brings the lever 66 into the normal position together with the eccentric 73 mounted on it which engages the arm 74 of the lever 66. The manner in 30 which the punching device operates is known. Likewise the manner in which the correct electromagnet and punch is selected with the aid of one single contact caused by a key is known:

45 Now the means which substantially form the subject-matter of the present invention are arranged on the combined typewriter and perforating machine represented in the accompanying drawings and briefly described above.

The means for canceling or eliminating one single perforated symbol consists of one simple key-lever corresponding to the key-lever 2, which however is not connected with 50 a type-lever, but has only a hook 50 with which it acts on a corresponding lever 52. The contact which is thereby occasioned causes a symbol to be perforated in the register band, which symbol can be used for 55 canceling or eliminating the action of the symbol which is perforated immediately beforehand. Accordingly, if it is necessary to rectify the position of the paper carriage of the typewriter this can be done by turning the spindle 35 by means of the handle

or knob 36. The second device which is used for canceling entire words is operated by means of a lever 80, as clearly shown in Figs. 1 and 2. This lever is revolute around the axle 81 and is connected with a lever 82 which has at its upper end a slot 83. In the latter there moves the pin 84 which is mounted on a draw rod 85. This rod is in the space between the body 1 of the typewriter and the frame 16 of the paper carriage. The rod has at one end a dog or pawl 86 which is attached revolute to the draw rod 85. The dog has an arm 87 against which a spring 88 presses. In its normal position the rod 85 is pulled to the left by a spring 89 which is attached on the one hand to the pin 90 on frame 1 and on the other hand to the rod 85 at 91. Thus the arm 87 of the dog 86 hits against a pin 92 attached to the body of the typewriter and brings the dog into its lowest position. If the paper carriage is to be drawn backward when a written word is being removed, the composer grasps the lever 80 and presses it slowly downward. The rod 85 is then pulled to the right and the dog 86 being under the action of the spring 88 is placed in the teeth of a rack 94 mounted on the frame of the paper carriage. When the rod 85 is moved still farther the paper carriage is driven to the right. The worm wheel 83 then rotates backward, the pawl 86 sliding over the teeth of the wheel 82. In order to make the perforated symbol, which is used for removing the corresponding group of holes, at the same time as the paper carriage is drawn backward, when the lever 80 is operated a contact is closed. For this purpose the lever 82 has a nose or extension 95, which the hook of a draw rod 96 engages. The latter rod leads into the lower part of the frame of the typewriter and is attached there to a lever 97, 98 which rotates around the axle 99. The arm 98 engages under an extension 51 of the contact lever 52. When the rod 96 is raised on account of the lever 80 being depressed, the lever arm 98 releases the contact lever 52 corresponding to it and closes an electric contact which operates the punching device in the same manner as the contacts made by the type-levers, so that a symbol is punched in the band, which symbol serves for removing the previously composed word.

The means for perforating the symbol for canceling entire lines are connected with the means for perforating the symbol for the end of the line. The band is perforated when the paper carriage is placed back to the beginning of the line and when a special key, the key for justifying a line, is depressed during the return movement of the carriage. For this purpose there is arranged on the paper carriage a rod 100, clearly shown in Figs. 1 and 3, which, after

a screw 101 has been loosened, can be shifted in the longitudinal direction of the paper carriage, in order to adjust the length of line. On the rod 100 two trippers or lifters 102 and 103 are attached by means of pins. On the tripper 102 there is revolvably mounted a pawl 104. An extension 105 of this pawl lies on a shoulder 106 of the tripper 103. When the typewriter is operated 10 the pawl slides from the right to the left over two ratchet wheels 107 and 108, but without rotating these wheels. When the paper carriage is pulled backward, the pawl 104 first drives the ratchet wheel 107 and 15 then the ratchet wheel 108 and rotates each wheel one tooth. A pawl 109 which is pressed by a spring 110 against the wheel 108 passes from below into the gaps between the teeth of this ratchet wheel. A leaf- 20 spring 111 is attached to the pawl 109, the end of which spring is opposite a contact screw 112. When the wheel 108 is rotated one tooth the pawl 109 must slide over the point of one tooth and is pressed downward 25 so far that the spring 111 contacts the contact screw 112. In this manner an electrical connection is made between the terminals 113 and 114, and this contact causes the symbol for the end of the line to be perforated. 30 A similar device is situated at the wheel 107. Here a pawl 115 which is under the influence of the spring 116 is provided with a leaf-spring 117 which contacts the contact screw 118 when the wheel 107 is rotated one tooth. 35 The electrical connection which is made between the terminals 119 and 120 causes, in certain cases, the line-cancellation symbol to be perforated. The wheels 107 and 108 are rotated when the paper carriage is moved 40 backward. In this case the symbol for the end of a line is always perforated owing to the wheel 108 rotating. The perforation of the symbol for canceling the line depends, however, besides on the rotation of the wheel 45 107, on the line-cancellation key being depressed in addition. This key, like that for canceling one single symbol, is provided with a contact device. The contacts at the key for canceling lines and at the pawl 115 50 are connected in series, so that the symbol for canceling lines can only be perforated when both places at which the circuit is interrupted are closed simultaneously. This 55 occurs when the key for canceling a line is kept depressed while the paper carriage is being moved back into its commencing position. The symbol for canceling a line is perforated before the symbol for the end of a line, corresponding to the positions of the 60 wheels 107 and 108.

The electrical connections between the contacts of the keys and the electromagnet coils of the perforating device are represented diagrammatically in Fig. 4. It is here presupposed that, in the case of the described

perforating device, each character and each operation which is to be done by the type-setting machine by means of the register band is represented by a perforated symbol which consists of two holes. Accordingly 70 each key must release two punches in the perforating device. The number of punches must be so great that the different positions of the perforations suffice for characterizing in a distinguishable manner all the characters, signs, and the like which occur. For example, if thirty-six different signs and the like are provided, at least nine punches must be employed in order to be able to make thirty-six different pairs of holes. In the 80 case of a larger number of characters and the like, the number of punches must be correspondingly increased. With the exception of the first and last, the electromagnets which release the punches have each 85 two coils of which the one is connected with the positive pole and the other with the negative pole of a source of current. In Fig. 4, 125 denotes the source of current; 126 and 127 are the two groups of electromagnet coils which are connected with the two poles of the source of current. The individual coils are differentiated within these groups by letters a_1 to h_1 and b_2 to i_2 90 respectively. The coil a_1 in the group 126 95 corresponds to the coil of the first electromagnet, whereas the coil i_2 in the group 127 corresponds to the coil of the last electromagnet. Of the remaining coils, those 100 which are denominated with like letters belong to the same electromagnet. From the coils a_1 to h_1 conductors a_3 to h_3 lead to 105 groups of contact levers 128 which correspond to the contact levers 52 in Fig. 1. From the electromagnet coils b_2 to i_2 conductors b_4 to i_4 likewise lead to groups of 110 contact screws 129 which correspond to the contact screws 55 in Fig. 1. The connection in groups of the contact screws 129 with the conductors b_4 to i_4 is such that a lever 128 115 which is connected with any one of the electromagnet coils a_1 to h_1 has opposite to it a contact screw which is connected with one of the electromagnets b_2 to i_2 , this electromagnet being always of higher place in the series than the electromagnet connected with the lever 128. In this manner with the aid of one single contact, two electromagnets 120 can be simultaneously energized, which will also be readily understood from the diagram of connections. The manner in which the contacts for the end of a line and for canceling a line are connected in circuit is seen at once from the diagram. In the case 125 of the contact for the end of a line the pawl 109 takes the place of a lever 52, and the contact screw 112 is used instead of the contact screw 55. In the case of the magnet for canceling a line a contact screw 129 in Fig. 4 is connected with the terminal 119 130

and corresponds to a contact screw 55 in Fig. 1. From the terminal 120 the conductor then leads to the coil of the second electromagnet which is to come into operation in the case of the concerned symbol. In Fig. 4 it is supposed that the electromagnet coils a_1 and b_2 belong to the symbol for canceling a line and that consequently the first of the contact screws 129 is to be connected 5 with the terminal 119 and the terminal 120 with the conductor b_4 . From the representation shown in Fig. 4 it will be readily understood that when canceling a line two contacts are to be closed simultaneously, 10 namely on the one hand the contact between a lever 128 and a screw 129, and further, the contact between the pawl 115 and the screw 118, when the current which occasions the perforation of the symbol for canceling 15 a line is to be able to flow. It is to be understood that the symbols for the individual cancellations or eliminations may be selected quite optionally.

The mechanical devices for executing the 20 principle of the invention which are here described may be modified in many ways. For example, for canceling individual symbols a second device can be provided in the same manner as has been above described 25 for canceling words. Also, for canceling lines the same device may be employed, it being taken for granted that the movement of the lever 82 can be made so great that the paper carriage is returned into the zero position. Likewise, for the canceling symbols, 30 keys could also be arranged by means of which a source of power is brought into play which returns the paper carriage.

When eliminating words and individual 35 symbols the composer must take care that the paper carriage is returned exactly into the correct position. For this purpose a pointer must be arranged on the typewriter which indicates exactly the position at which the type makes an impression. Such a 40 pointer is clearly represented in Figs. 1 and 5. On the body of the frame of the machine below the paper carriage there is arranged in a pedestal 130 a pointer 132 revoluble around the pin 131. The pointer which is 45 represented more particularly in Fig. 5 projects through the paper carriage and is so shaped that when the platen roll 8 is turned up the pointer lies at 133 at the place where the types strike. The pointer is enlarged at 50 its lower end in order to securely journal the same, and has at the place where it lies against the paper a beveled edge 134 which denotes exactly the place where the types 55 print. When setting the paper carriage after removing a word or character, the carriage must be so adjusted that the last remaining character just contacts the edge 134 from the left. The pointer is revoluble in 60 the pedestal 130, so that it can be moved

away when the paper carriage is turned up. When returning the platen roll 8 into the normal position an extension 136 which is attached to the pointer 132 lies against a stop 137 and prevents the pointer sliding on 70 the paper during writing. In order to be able to exactly adjust the paper carriage after a word has been canceled, with the key for the space between two words there may be connected a type-lever which at each 75 space between two words strikes a fine straight line or a similar mark on the paper, this line being so placed that it can serve as an adjusting mark after the removal of a word.

What I claim as my invention and desire to secure by Letters Patent is:

1. In means for making the operating bands for setting type, the combination of a punching device, with a plurality of means 85 for punching in an operating band different representations of different corresponding canceling or stop actions.

2. In means for making the operating bands for setting type, the combination of a 90 punching device for punching representations of characters in a band, with a plurality of means for punching in the band representations of stops or canceling actions for canceling single characters, stop or canceling 95 actions for canceling words, and stop or canceling actions for canceling lines represented in the band.

3. In means for making the operating bands of automatic type-setting machines, 100 the combination of a punching device, a typewriter, a paper carriage on the typewriter, means for moving the carriage backward, and means for punching simultaneously the representation of a stop or canceling action.

4. In means for making register bands for setting type, wherein a typewriter is combined with a perforating device and a plurality of electrical contacts adapted to be 110 closed by the typewriter for actuating the perforating device, the combination with the paper carriage of the typewriter, of means for moving the carriage backward and means connected with the latter means for simultaneously closing one of said contacts.

5. In means for making register bands for setting type, wherein a typewriter is combined with a perforating device and a plurality of electrical contacts adapted to be 115 closed by the typewriter for actuating the perforating device, the combination, with the paper carriage of the typewriter, of means for moving the carriage backward and a lever connected with the latter means for 120 simultaneously closing one of said contacts.

6. In means for making register bands for setting type, wherein a typewriter is combined with a perforating device the combination, with the paper carriage of the type- 125

- writer, of a shifting device comprising a rack on said carriage, a spring-pulled rod carrying a spring-pressed pawl adapted to engage said rack, and a lever movably attached to said rod for moving the same against its spring; and means connected with said shifting device for simultaneously punching stop or canceling holes in the perforated band.
10. 7. In means for making register bands for setting type, wherein a typewriter is combined with a perforating device and a plurality of electrical contacts adapted to be closed by the typewriter for actuating the perforating device, the combination, with the paper carriage of the typewriter, of a shifting device comprising a rack on said carriage, a spring-pulled rod carrying a spring-pressed pawl adapted to engage said rack, and a lever movably attached to said rod for moving the same against its spring; and means connected with said shifting device for simultaneously closing one of said contacts.
15. 8. In means for making register bands for setting type, wherein a typewriter is combined with a perforating device and a plurality of electrical contacts adapted to be closed by the typewriter for actuating the perforating device, the combination, with the paper carriage of the typewriter, of a shifting device comprising a rack on said carriage, a spring-pulled rod carrying a spring-pressed pawl adapted to engage said rack, and a lever movably attached to said rod for moving the same against its spring; and a second lever positively actuated by the former lever for simultaneously closing one of said contacts.
20. 9. In means for making register bands for setting type, wherein a typewriter is combined with a perforating device and a plurality of electrical contacts adapted to be closed by the typewriter for actuating the perforating device, the combination, with the paper carriage of the typewriter, of a shifting device comprising a rack on said carriage, a spring-pulled rod carrying a spring-pressed pawl adapted to engage said rack, and a lever movably attached to said rod for moving the same against its spring; and means adapted to be actuated by said driving means for closing one of said contacts.
25. 10. In means for making register bands for setting type, wherein a typewriter is combined with a perforating device and a plurality of electrical contacts adapted to be closed by the typewriter for actuating the perforating device, the combination, with the paper carriage of the typewriter, of a rod movable thereon, driving means on said rod, and means adapted to be actuated by said driving means for closing one of said contacts.
30. 11. In means for making register bands for setting type, wherein a typewriter is combined with a perforating device and a plurality of electrical contacts adapted to be closed by the typewriter for actuating the perforating device, the combination, with the paper carriage of the typewriter, of a rod movable thereon, driving means on said rod, and means connected with said shifting device for simultaneously closing one of said contacts.
35. 12. In means for making register bands for

setting type, wherein a typewriter is combined with a perforating device and a plurality of electrical contacts adapted to be closed by the typewriter for actuating the perforating device, the combination, with the paper carriage of the typewriter, of a rod movable thereon, driving means on said rod, an electrical contact in series with one of said former contacts, a pawl adapted to close the latter contact, and a ratchet wheel adapted to be rotated by said driving means and actuate said pawl.

10. In means for making register bands for setting type, wherein a typewriter is combined with a perforating device and a plurality of electrical contacts adapted to be closed by the typewriter for actuating the perforating device, the combination, with the paper carriage of the typewriter, of a rod movable thereon, a lifter (103) having a shoulder on said rod, a second lifter (102) on said rod, a pawl (104) revoluble on the latter lifter and normally resting on said shoulder, a ratchet wheel (107) adapted to be actuated by said pawl (115), carrying a spring (117) in series with one of said former contacts, said ratchet wheel being adapted to move said latter pawl and cause said spring and said screw to contact.

In testimony whereof I have signed my name to this specification in the presence of two subscribing witnesses.

HEINRICH DREWELL.
